CHARLES P. BOSSERT, OF MILWAUKEE, WISCONSIN, ASSIGNOR TO PFISTER & VOGEL LEATHER CO., OF MILWAUKEE, WISCONSIN, A CORPORATION OF WISCONSIN.

MACHINE FOR TREATING HIDES AND SKINS.

1,421,662.

Specification of Letters Patent. Patented July 4, 1922.

Application filed December 16, 1920. Serial No. 431,151.

To all whom it may concern:

Be it known that I, CHARLES P. BOSSERT, a citizen of the United States, residing at Milwaukee, county of Milwaukee, State of Wisconsin, have invented a new and useful Machine for Treating Hides and Skins, of which the following is a specification.

My invention relates to a novel construction of a machine for treating hides and skins and relates more particularly to apparatus for applying hair removing compounds thereto, such as a sulfid compound, which is usually composed of sulfid of soda and lime which is applied to the flesh side 15 of a skin and is allowed to remain on the skin or hide for a short time so as to penetrate through it and has the effect of loosening the hair, so that it may be readily removed by a subsequent operation.

20 This sulfid compound is of a thick plastic nature, and by my novel construction, sulphid solutions of any consistency can be agitated and applied to any class of leather with absolutely unvarying uniformity, the 25 quantity applied being readily varied to suit requirements and much better results being obtained than by hand labor.

Other important advantages of my invention are the saving of the hair by my novel 30 machine as considerably less of this is damaged than by hand labor, and the sulphid is not wasted as any surplusage is pumped back into the tank.

To the above ends, my invention consists 35 of novel means for agitating and applying the sulphid compound and of a novel attachment to the machine of my prior U. S. Patent No. 1,300,920, all as will be herein-after fully set forth and pointed out in the 40 claims.

It further consists of a novel construction of sulfid pan or hopper, which is supported in a novel manner from the housing of the machine so as to give ready access to the 45 interior thereof.

The invention also consists of a novel spraying device juxtaposed to the under side of the bolster employed for removing any surplusage of the sulfid compound, which 50 remains on said bolster after passing the scraper.

It further consists of a novel manner of constructing, assembling and supporting the

hopper or pan which receives and delivers the sulfid compound to the feed roll, whereby 55 said pan and its adjuncts can be readily disconnected from the machine housing and thus rendered readily accessible when desired.

For the purpose of illustrating my invention, I have shown in the accompanying drawings forms thereof which are at present preferred by me, since they will give in practice satisfactory and reliable results, although it is to be understood that the 60 various instrumentalities of which my invention consists can be variously arranged and organized and that my invention is not limited to the precise arrangement and organization of these instrumentalities as 65 herein shown and described.

Figure 1 represents a perspective, front view of a sulphid painting machine or a machine for treating hides, skins and the like, embodying my invention.

Figure 2 represents a back perspective view of Figure 1.

Figure 3 represents, on an enlarged scale, a plan view of certain novel features appertaining to my present invention.

Figure 4 represents an end view of Figure 3.

Figure 5 represents a diagrammatic plan view, showing the driving mechanism, certain of the parts being omitted for clearness 85 of illustration.

Figure 6 represents, on a reduced scale, a section on line 6-6 of Figure 3.

Similar numerals of reference indicate corresponding parts.

Referring to the drawings.

1 designates my novel sulphid machine, the same comprising the framework 2, which has mounted in the front thereof the drum 3, and in the rear thereof the drum 4 over 95 which passes the endless apron, belt or bolster 5, upon which the hides or skins to be treated are placed, said apron moving the hides under the mechanism for applying the sulfid compound thereto, and said drums being supported and rotated by any suitable driving mechanism, as the driving shaft 6.

7 designates a pinion on said shaft 6 in mesh with the gear 8 mounted on the shaft 9 which carries the pinion 10 in mesh with 100 the gear 11, mounted on the shaft 12 on

which latter the drum 4 is mounted, it being understood that the rotation of the drum 4 actuates the endless belt or apron 5 and the drum 3, power being applied to the shaft 5 6 by the pulleys 13.

14 designates a sprocket wheel mounted on the shaft 9 around which passes the sprocket chain 15, whereby the sprocket wheel 16 fast on the shaft 17 is driven. 18 10 designates a pinion fast on the shaft 17, and in mesh with the pinion 19, which rotates in unison together with the sprocket wheel 20 on the shaft 21, as will be understood from the top of Figure 5 and the left of Figure 1. 15 22 designates a sprocket chain driven by the sprocket wheel 20, whereby the sprocket wheel 23, mounted on the shaft 24 is driven. The shaft 24 carries the feed roller 25 which is rotated at a relatively slow rate of speed 20 and at its end opposite to the sprocket wheel 23 said shaft carries the sprocket wheel 26 (see Figure 3) around which passes the sprocket chain 27, which drives the sprocket wheel 28, carried on the shaft 29, which has 25 thereon the roll 30, which is provided with the agitator or helical surfaces 31 (see Figure 3) which are juxtaposed to the feed roll 25.

32 designates the sulfid distributing means the same comprising the shaft 33 and a plurality of radially projecting flexible strips or wiping elements 34, which may be of any desired number, and secured to the shaft 33 in any desired manner, said strips extending across the machine throughout the entire 35 length of the feed roller 25.

The shaft 33 and its adjuncts may be rotated from any suitable source of power as by a belt applied to the pulley 60 and is preferably rotated at a considerably greater 40 speed than the feed roller 25, it being apparent that the parts are so positioned that when the shaft 33 is rotated in the direction of the arrow in Figure 4 the flexible strips 19 will contact with the surface of the feed roller 45 25 removing the adhering sulfid compound therefrom and throwing it down towards the apron or bolster 5. The feed roller 25, the agitators 31 and the sulfid distributing means 32 may be enclosed by a suitable guard or 50 casing 35, and while the sulfid pan or hopper 36 may be variously arranged and supported, I preferably construct the same of the end members 37, and the bottom or body member 38, having the end brackets or arms 55 39, terminating in the upright end flanges 40, which are bolted or otherwise secured to the flanges 41 of the housing 42, which carries the bearings for the feed roll 25 and the distributing means 32 both ends of the pan 60 or hopper 36 being substantially the same, as will be understood from Figures 1, 3 and 4.

The sulfid compound is pumped from the lower receptacle 43, see Figure 2, by means 65 of the pump 44 and the pipe 45 into the tank

46, which is supported above the machine in any suitable manner, said tank discharging the sulfid compound through the pipe 47 and valve 48 to the hopper or pan 36.

49 designates the overflow pipe for the sulfid compound, whose lower end discharges into the receptacle 43 (as seen in Figure 2) said receptacle also receiving the surplus sulfid compound from the end of the trough 50, which is preferably inclined towards said receptacle and catches any surplusage of said compound which may be scraped from the bottom of the bolster 5 by the scraper or scrapers 51, seen in Figures 1 and 2. In case of any of the sulfid compound remaining on the bolster 5, after passing the scraper 51, the same is removed by the water spray pipe 52 having the valve 53 and the ports 54 therein discharging against the bottom of said bolster, as will be understood from Figures 1 and 5, the water being caught in the trough 55, which may have a drain pipe, as 56, leading to any desired point. The bolster 5 may be provided with an intermediate supporting roll 57, see Figure 2, and the sprocket chain 22 may be provided with a chain tightener 58, as seen in Figure 1. The agitator 31 for the sulfid compound is preferably made in cylindrical sections 59, each section having the two helical members cast 95 thereon, as seen in Figure 3, said sections being keyed or fast on their supporting shaft, so as to rotate in unison therewith, but being readily disconnected therefrom according to requirements when the hopper or pan 100 36 is taken apart. It will be understood by those skilled in the art that the sulfid compound is a material of a thick plastic nature and the agitator 31 has an important function in keeping the contents of the pan or hopper 36 at all times in a proper state of agitation, so that the sulfid compound will be properly subjected to the action of the feed roll 25 and applied with unvarying uniformity to the hide, skin or other article 105 to be treated, and in case of any clogging occurring in the pan or hopper 36, the same is readily accessible upon the removal of the bolts securing the ends 37 and the arms or brackets 39 in position.

The operation is as follows:—

The hides, skins or other articles to be treated are placed upon the conveyor or bolster 5 at the forward or front end of the machine, as seen in Figure 1 and as they 120 pass under the feed roll and distribution means 32, the latter supplies to the surface of the skin a uniform coating of the sulfid compound, since the rapidly rotating wiping strips 34 strike the surface of the feed roller in rapid succession, remove the sulfid therefrom and throw it down on to the surface of the hide, said compound being supplied to the flesh side thereof, and permeating through it. The sulfid compound by rea- 130

son of the employment of the agitating devices 31, is at all times kept at the desired consistency, so that it can be applied with unvarying uniformity and the various mov-

5 ing parts are so timed that the sulfid compound is thrown on the surface of the hide or skin in a substantially continuous manner, so that the hide receives a uniform coating of said compound, and when the hides have 10 travelled to the rear end of the machine as seen in Figure 2 they are removed therefrom by hand or any other appropriate means.

The scraper or scrapers 51 which may be two in number remove any excess of the 15 sulfid compound which falls into the trough 50 as will be understood from Figure 2 and in case of any of the sulfid compound remaining on the bolster after passing the scraper, the same is removed by the water 20 spray which is directed against the bottom of the bolster through the medium of pipes 52.

I desire to call special attention to the collocation of the agitator 31, with respect 25 to the feed roll 25 and the distributing means 32, the general collocation and direction of rotation of these elements being understood from Figure 6, wherefrom it will be seen that the sulfid compound will be at all times 30 properly agitated and directed towards the feed roller so as to adhere to the surface thereof in the form of a thin sheet and will be properly removed therefrom and directed upon the hide, skin or other article to be 35 treated. My invention is particularly applicable for applying to any article, a material of a thick, plastic nature in an expeditious and mechanical manner and while I have described my invention as being par- 40 ticularly applicable to hide treating machines, it will be understood that it is equally useful in various other applications and in other arts.

It will now be apparent that I have de- 45 vised a novel and useful sulphide machine which embodies the features of advantage enumerated as desirable in the statement of the invention and the above description, and while I have, in the present instance, shown 50 and described a preferred embodiment there- of which will give in practice satisfactory and reliable results, it is to be understood that the same is susceptible of modification in various particulars, without departing 55 from the spirit or scope of the invention or sacrificing any of its advantages.

Having thus described my invention, what I claim as new and desire to secure by Letters Patent, is:—

60 1. An apparatus for applying substances to hides and the like having means for delivering the substance to a position adjacent the hide, a flexible strip for receiving a portion of the substance therefrom, means for 65 moving said strip at a comparatively high

velocity to throw the substance received thereby onto said hide and an agitating device located in proximity to said substance delivering means.

2. An apparatus for applying elastic sub- 70 stances to hides and the like, having means forming a surface for delivering a thin sheet of the substance to a position adjacent the hide, a plurality of spaced apart flexible strips, each extending substantially the 75 width of said surface, for wiping portions of the substance therefrom, means for moving said strips at a comparatively high velocity to throw the removed substance onto said hide, and a rotatable agitating de- 80 vice located in proximity to said delivering means.

3. Apparatus for applying plastic sub- 85 stances to articles, comprising a rapidly rotating member having a plurality of radially projecting flexible strips, a rotary surface to which the plastic substance is adapted to adhere, said flexible strips being adapted to rotate in contact with said surface to remove the plastic substance therefrom and to 90 distribute it upon the surface of the article and a rotary agitator for said substances located in proximity to said rotary surface.

4. Means for applying a plastic substance to an article comprising a feed roll, distrib- 95 uring means in proximity thereto under which said article passes, said distributing means having at least one radially projecting flexible strip adapted to rotate in contact with the surface of the feed roll to remove 100 the plastic substance therefrom and throw it onto the surface of the article and a rotary agitator located in proximity to said feed roll.

5. Means for supplying a plastic substance 105 to an article comprising a moving surface to which some of the plastic substance is adapted to adhere, a rotary member adapted to revolve adjacent to said surface, a radially projecting flexible strip associated with said 110 member, adapted to contact with said surface to remove the plastic substance therefrom and to throw it onto the surface of the article, and an agitator for said substance, located in proximity to said moving surface. 115

6. Means for applying plastic substances to articles comprising a feed roll, distribut- 120 ing means cooperating therewith and comprising a plurality of radially projecting flexible strips adapted to contact with the surface of the feed roll, means to rotate the feed roll in one direction at a relatively slow speed and to rotate the distributing means in the opposite direction at a relatively fast speed, whereby the plastic sub- 125 stance is removed from the surface of the feed roll and thrown onto the surface of the article and an agitator for said plastic substance located in proximity to said feed roll.

7. An apparatus for applying plastic substances to hides and the like having means for delivering the substance to a point adjacent the hide, means presenting an edge 5 for receiving a portion of the substance therefrom, means for moving said last named means at a comparatively high velocity to throw the substance received thereby onto said hide, an agitator located in proximity 10 to said delivering means and means for rotating said agitator.
8. An apparatus for applying plastic substances to hides and the like, having means for delivering the substance to a point adjacent the hide, a strip for receiving a portion of the substance therefrom, means for moving said strip at a comparatively high velocity to throw the substance received thereby onto said hide, and a rotary sectional 15 agitator located in proximity to said delivering means.
9. An apparatus for applying plastic substances to hides and the like, having means for delivering the substance to a point adjacent the hide, a plurality of spaced apart flexible strips for receiving the substance therefrom, means for rotating said strips at a comparatively high velocity to throw the substance received thereby onto said 20 hide, an agitator in proximity to said delivering means, and means for rotating said agitator.
10. An apparatus for applying plastic substances to hides and the like, having means forming a surface for delivering a thin sheet of the substance to a position adjacent the hide, a plurality of spaced apart, flexible strips extending substantially the width of said surface for removing portions 25 of the substance therefrom, means for moving said strips at a comparatively high velocity to throw the removed substance onto said hide, an agitator in proximity to said delivering means, and means for rotating said agitator.
11. In an apparatus for applying plastic substances to hides or other articles, the combination of a conveyor, means for delivering the plastic substance to a point adjacent said conveyor, means for removing portions of the substance from the delivering means and throwing it onto an article on the conveyor, means for removing the substance which falls on the conveyor and returning such substance to the delivering 30 means, and an agitator located in proximity to the latter.
12. In an apparatus for applying plastic substances to hides or other articles, the combination of a conveyor, means for delivering the plastic substance to a point adjacent the conveyor, a strip for removing portions of the substance from said means and throwing such substance onto an article on the conveyor, a seraper for removing the 35 substance which falls on the conveyor and a water spray pipe discharging against the bottom of said conveyor.
13. In an apparatus for applying plastic substances to hides or other articles, the combination of an article support, means for delivering the plastic substance to a point adjacent the article on said support, means for removing the substance from said delivering means and throwing such substance onto the article on said support, means for removing the substance which falls on said support and returning such substance to said delivering means, and a rotary agitator located in proximity to said delivering 40 means.
14. The combination with mechanism for applying a plastic substance to hides or other articles, of an article conveyor, a scraper for removing the substance which falls on said conveyor, means for returning such removed substance to the substance applying mechanism, and a water spray pipe extending transversely of said conveyor for removing any substance therefrom not removed by said scraper.
15. An apparatus for applying a plastic substance to hides, including a conveyor for carrying a hide through the machine with one side exposed, means for delivering the substance to a point adjacent the conveyor, means driven at a higher angular velocity for removing portions of the substance from said delivering means and throwing such removed substance onto the exposed side of the hide and a rotary agitator located in proximity to said delivering means.
16. A hide treating machine, comprising a conveyor for moving the hide through the machine, a rotary agitator, a feed roll under which the hide passes for applying a plastic substance to the hide, said feed roll having a surface to which some of the plastic substance adheres and a plurality of spaced apart flexible strips rotating in contact with said surface and adapted to strike the same thereby to remove the substance from said surface and throw it onto the hide.
17. In a machine of the character stated, the combination of a hopper for the sulfid compound having detachable end pieces and a body portion provided with deflected end brackets having flanges thereon and housing flanges to which said bracket flanges are secured.
18. In a machine of the character described, an article conveyer, a hopper for receiving the plastic substance, a rotary agitator in said hopper, a feed roll in proximity to said agitator, means driven at a high angular velocity for removing portions of said substance from said feed roll, an article conveyer below said agitator and feed roll, means for actuating said conveyer, means

for actuating said feed roll and power transmission devices common to said feed roll and agitator.

19. In a machine of the character described, the combination of an agitator made up in sections, each section having oppositely disposed ridges thereon, a feed roll in proximity to said agitator, and a distributing device in proximity to said feed roll and having a flexible strip adapted to contact therewith.

20. In a machine of the character described, the combination of an agitator made up in sections, each section having oppositely disposed ridges thereon, a feed roll in proximity to said agitator, and a distributing device in proximity to said feed roll and having a flexible strip adapted to contact therewith, in combination with means for rotating said distributing device at a relatively high speed and in a direction opposite to the rotation of said feed roll.

21. In a machine of the character described, an agitator, a feed roll in proximity thereto, power transmission devices common to said agitator and feed roll, means for rotating said feed roll, a flexible strip adapted to contact with said feed roll, and means for rotating said strip at a relatively high velocity with respect to said feed roll.

22. In a machine of the character described, a driving shaft having a pinion 7 thereon, a gear 8 in mesh with said pinion, a shaft 9 on which said gear is mounted, a pinion 10 on the opposite end of said shaft, a gear 11 in mesh with said pinion, a shaft 12 in which said latter gear is mounted, a drum 4 mounted on said shaft 12, an opposite drum 3, a bolster common to said drums, a sprocket wheel 14 on said shaft 9, a shaft 17, a sprocket wheel 16 thereon, a sprocket chain common to said sprocket wheels, a pinion 18 on said shaft 17, a pinion 19 in mesh with said latter pinion, a sprocket wheel 20, a shaft 21 on which said pinion 19 and sprocket wheel 20 are fast, a feed roll 25, a shaft for said feed roll carrying the sprocket wheel 23, a sprocket chain 22 common to said sprocket wheels 20 and 23, a sprocket wheel 26 on the opposite end of said feed roll shaft, an agitator, an agitator shaft 29, a sprocket wheel 28 on said agitator shaft, and a sprocket chain common to said sprocket wheels 26 and 28.

23. In a machine of the character described, a driving shaft having a pinion 7 thereon, a gear 8 in mesh with said pinion,

a shaft 9 on which said gear is mounted, a pinion 10 on the opposite end of said shaft, a gear 11 in mesh with said pinion, a shaft 12 on which said latter gear is mounted, a drum 4 mounted on said shaft 12, an opposite drum 3, a bolster common to said drums, a sprocket wheel 14 on said shaft 9, a shaft 17, a sprocket wheel 16 thereon, a sprocket chain common to said sprocket wheels, a pinion 18 on said shaft 17, a pinion 19 in mesh with said latter pinion, a sprocket wheel 20, a shaft 21 on which said pinion 19 and sprocket wheel 20 are fast, a feed roll 25, a shaft for said feed roll carrying the sprocket wheel 23, a sprocket chain 22 common to said sprocket wheels 20 and 23, a sprocket wheel 26 on the opposite end of said feed roll shaft, an agitator, an agitator shaft 29, a sprocket wheel 28 on said agitator shaft, and a sprocket chain common to said sprocket wheels 26 and 28, in combination with a flexible strip coacting with said feed roll, and means for rotating said strip at a higher speed than said feed roll.

24. In a hide treating machine, a hopper for the sulfid compound having detachable end pieces, and a body portion provided with end brackets having flanges thereon, a housing having flanges to which said bracket flanges are secured, an agitator in said hopper, and means for actuating said agitator.

25. In a hide treating machine, a hopper for the sulfid compound having detachable end pieces, and a body portion provided with end brackets having flanges thereon, a housing having flanges to which said bracket flanges are secured, an agitator in said hopper, and means for actuating said agitator, in combination with means coacting with said agitator for applying the sulfid compound to a hide.

26. In a hide treating machine, a hopper for the sulfid compound having detachable end pieces, and a body portion provided with end brackets having flanges thereon, a housing having flanges to which said bracket flanges are secured, an agitator in said hopper, and means for actuating said agitator in combination with means coacting with said agitator for applying the sulfid compound to a hide, said agitator being composed of cylindrical sections having helixes thereon.
